US0D1028591S

(12) **United States Design Patent** (10) **Patent No.:** **US D1,028,591 S**
(45) **Date of Patent:** **** May 28, 2024**

(54) **FURNITURE FRAME PART**

(71) Applicant: **Wood Tube Sweden AB**, Grums (SE)

(72) Inventors: **Kurt Härdig**, Langserud (SE); **Patrik Kämpe**, Grums (SE); **Tobias Söderbom Olsson**, Karlstad (SE)

(73) Assignee: **Wood Tube Sweden AB**, Grums (SE)

(**) Term: **15 Years**

(21) Appl. No.: **35/515,359**

(22) Filed: **Apr. 8, 2022**

(80) **Hague Agreement Data**

Int. Filing Date: **Apr. 8, 2022**

Int. Reg. No.: **DM/222609**

Int. Reg. Date: **Apr. 8, 2022**

Int. Reg. Pub. Date: **Oct. 14, 2022**

(51) **LOC (14) Cl.** **06-06**

(52) **U.S. Cl.**

USPC **D6/712**; D25/122

(58) **Field of Classification Search**

USPC D6/702, 707.24, 709, 709.2, 712; D23/266; D25/122

CPC A47B 95/00; A47B 96/14; A47B 96/1425; A47B 96/1433

See application file for complete search history.
